UNITED STATES PATENT OFFICE.

WILEY B. HIX, OF ROME, GEORGIA.

IMPROVED ARRANGEMENT OF FLUES FOR DRYING TOBACCO.

Specification forming part of Letters Patent No. 31,081, dated January 8, 1861.

To all whom it may concern:

Be it known that I, WILEY B. HIX, of Rome, in the county of Floyd and State of Georgia, have invented a new and Improved Mode of Drying Tobacco; and I do hereby declare that the following is a full, clear, and exact description of the same, reference being had to the annexed drawings, making a part of this specification, in which—

Figure 1 is a side sectional view of my invention, taken in the line xx , Fig. 2; Fig. 2, a horizontal section of the same, taken in the line yy , Fig. 1.

Similar letters of reference indicate corresponding parts in the two figures.

To enable those skilled in the art to fully understand and construct my invention, I will proceed to describe it.

A represents a building, which may be of rectangular form and of any suitable dimensions, and B B' C are flues, which are at the bottom of the building, and communicate with a proper fire-chamber at the outer side of the building. The flues may be of masonry or cast-iron.

B B' are the two principal flues, which are united at their back ends by a semicircular passage, a, the latter communicating with the smoke-stack D, as shown clearly in Fig. 2.

The flues B B' are connected about midway by the flue C, at one end of which there is a

damper, E, and the flue B, at the opposite end of C, is provided with two dampers, F F', one at each side of the flue C. (See Fig. 2.)

The operation is as follows: The tobacco to be dried is spread or properly disposed within the house or building A, and when an even distribution of heat is required within the building the heat from the furnace is allowed to pass equally through the two flues B B' and flue C, all the dampers being open. If the heat is required at one side only—the side, for instance, over the flue B—the damper E is closed, and also dampers F F'. If a gentle heat is required over the flue B', the dampers F F' are partially opened, and if a heat is required over a flue, C, the damper E is opened, and also damper F'. Thus it will be seen that the heat is placed under the complete control of the operator.

Having thus described my invention, what I claim as new, and desire to secure by Letters Patent, is—

The employment, in the drying of tobacco, of a system of flues, B B' C, and chimney D, with dampers E F F', arranged and operating together within a suitable inclosure, A, as and for the purposes herein shown and described.

WILEY B. HIX.
